FIG. 2

FIG. 1

FIG. 5

FIG. 3

FIG. 4

FIGURE 1 is a front elevational view of a combined jar and closure cap with the closure cap removed, showing my new design;

FIGURE 2 is a top plan view thereof with the closure removed;

FIGURE 3 is a side elevational view thereof. The side not shown is the same as the side shown. The top of the closure cap is flat and plain.

FIG. 4 is an enlarged fragmentary cross-sectional view taken on the line 4—4 of FIG. 3; and

FIG. 5 is an enlarged fragmentary cross-sectional view taken on the line 5—5 of FIG. 3.

I claim:

The ornamental design for a combined jar and closure cap, as shown and described.
